DESIGN FOR A COMBINATION STEAM TABLE AND FOOD SERVICE COUNTER

Stanley H. Knight, Chicago, Ill.

Application June 23, 1939, Serial No. 85,652

Term of patent 3½ years

To all whom it may concern:

Be it known that I, Stanley H. Knight, a citizen of the United States and resident of Chicago, in the county of Cook and State of Illinois, have invented a new, original, and ornamental Design for a Combination Steam Table and Food Service Counter, of which the following is a specification, reference being had to the accompanying drawing, forming a part thereof.

The figure is a rear perspective view of a combination steam table and food service counter, showing my new design.

The undisclosed sides and front of the article are substantially plain. The two lower rear doors in closed position are substantially plain. The central rear door is slidable over the opening at the left thereof.

I claim:

The ornamental design for a combination steam table and food service counter, as shown and described.

STANLEY H. KNIGHT.
